UNITED STATES PATENT OFFICE.

FRANK W. SIMONS, OF LEWISTOWN, ILLINOIS, ASSIGNOR OF ONE-HALF
TO DAYTON BLACKABY, OF LEWISTOWN, ILLINOIS.

GATE-LATCH.

SPECIFICATION forming part of Letters Patent No. 781,792, dated February 7, 1905.

Application filed December 23, 1903. Serial No. 186,348.

To all whom it may concern:

Be it known that I, FRANK W. SIMONS, a citizen of the United States, residing at Lewistown, in the county of Fulton and State of Illinois, have invented a new and useful Gate-Latch, of which the following is a specification.

This invention relates to gate-latches, and has for its object to provide an improved device of this character for latching a gate to a stub-post over which the gate swings. It is furthermore designed to effect an automatic engaging of the latch members when the gate is swung to a position over the stub-post and to provide for the convenient release of the latch when it is desired to open the gate.

Another object is to embody the parts of the latch in such form as to facilitate their attachment to the bottom of the gate and the top of the stub-post and also to have the members braced against lateral strains when interengaged.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings illustrative of the invention, in which corresponding parts are denoted by like designating characters, Figure 1 is a side view of a pair of gates with the improved device applied. Fig. 2 is a side view, and Fig. 3 is an end view, enlarged, of the improved device. Fig. 4 is a longitudinal sectional view. Figs. 5 and 6 are perspective views, enlarged, of the two members comprising the improved device disconnected. Fig. 7 is a cross-sectional view of the lower latch member.

Like characters of reference designate corresponding parts in each and every figure of the drawings.

The main gate is represented at 10, mount-

ed to swing on a post 11, as by hinges 12, in 50 the usual manner and will be of the usual size. A supplemental or extension gate is shown at 13 and hinged to swing, as at 14, upon a post 15, the free ends of the two gates coupled detachably by a latch, as at 16, as shown. The 55 supplemental gate will generally be smaller than the main gate and will be opened only when required to permit abnormally large objects to pass through, as above noted. Beneath the outer or free end post 17 of the 60 smaller gate when closed a shorter post 18 is embedded, with its upper end projecting only a short distance above the ground, (indicated at 19.) Attached to the bottom of the post 17 and to the top of the post 18 are cap members 20 21, the cap members having spaced side flanges embracing the sides of their respective posts and connected thereto by transverse bolts 24 25, as shown. The cap member 20 is provided with an integral tongue 70 26, cleft from its bottom and offset therefrom, while the cap member 21 is provided with a similarly-formed, but reversely-disposed, integral tongue 27, offset from its top, as shown. The tongues 26 27 are reinforced, respectively, at their "root" ends by bent plates 28 29, riveted thereto and to the cap members, as shown. Attached to one of the tongues, preferably to the one on the cap member 21, is a resilient latch-bar 30, having its free end 80 barbed, as at 31, and extending beyond the end of the cap member, as shown.

When the smaller gate 13 is swung to its closed position, the tongues 26 and 27 of the latch members approach one another in opposite directions, and as the tongue 27 is offset upon the upper side of the member and the tongue 26 is offset upon the under side of the upper member the tongue 26 will pass beneath the tongue 27, with the bottom of the upper member upon the top of the lower member. The tongue 26 will occupy the space or slot from which the tongue 27 has been displaced or offset, while the notched end of the member 30 will snap over the rear edge of the cap member 20, and thereby prevent longitudinal

separation of the members. By reason of the tongues 26 and 27 fitting in the slots or openings in the members 21 and 20, respectively, there is an interlocked engagement between the members to brace the same against lateral strains, and thereby maintain the same rigidly connected when interlocked. If the tongue 26 were omitted, there would be only an ineffectual bracing against lateral strains by the tongue 27 fitting in the slot or opening of the member 20. The interlocking and interengaging tongues thus coact with the spring-latch-bar to form a firm, strong, and automatically-closing coupling means to hold the smaller gate closed and with sufficient rigidity to act as a support for the free end of the larger gate 10 and to carry the socket member 32 of the latch 16, as shown, while at the same time easily releasable by merely depressing the protruding barbed end 31 of the spring-latch, as by the foot of the operator, and swinging the smaller gate open. In closing it is only necessary to forcibly "enter" the interlocking tongues into their respective opposing cap members and close the gate above its stop-post 18, when the latch member 30 31 will be automatically engaged, as will be obvious. The cap members, together with their respective integral tongues and flanges, will preferably be "struck-up" or pressed from steel or iron, but may be formed of cast, malleable, or other metal, if preferred. From the foregoing description it will be understood that the locking arrangement between the supplemental gate 13 and the stub-post 25 is entirely independent of the gate 10, and the latch connection between the two gates is independent of the engagement between the supplemental gate and the stub-post, whereby it is possible to open and close the main gate without releasing the supplemental gate, and said supplemental gate may be opened to increase the size of the gateway whenever desired. The parts may be of any suitable size or strength and may be modified as to proportion

tions and other minor details of construction without departing from the principle of the invention or sacrificing any of its advantages.

Having thus described my invention, what I claim is—

1. A device of the class described comprising two cap members for attachment respectively to the free end of a gate and a support over which it is positioned when closed, said cap member having longitudinally-disposed tongues for interlocking engagement when the gate is closed, and with reinforcing-plates connecting said tongues at their roots with said caps, substantially as described. 60

2. A gate-latch of the character described comprising opposite cap members, one member carrying pendent attaching-flanges and the other having upstanding attaching-flanges, each member having spring-tongues cleft 65 therefrom, and one of the tongues having a headed latch projected beyond the free end thereof for engagement with the other cap. 60

3. The combination of a swinging gate, a stub-post driven into the ground and over 70 which the outer end bar of the gate is capable of passing, a lower plate member spaced above the stub-post and provided with pendent attaching-flanges embracing and secured to said post, an upper plate member spaced below the 75 outer end bar of the gate and provided with upstanding flanges embracing and connected to said end bar, said plates being provided with corresponding reversely-arranged spring-tongues cleft therefrom, and a headed latch carried by and projected beyond the free end of one of the tongues for engagement with that edge of the other plate adjacent the root of the tongue thereof. 80

In testimony that I claim the foregoing as 85 my own I have hereto affixed my signature in the presence of two witnesses.

FRANK W. SIMONS.
